UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-RIGGING FOR RAILWAY-CARS.

1,073,242.

Specification of Letters Patent. Patented Sept. 16, 1913.

Application filed January 13, 1913. Serial No. 741,701.

To all whom it may concern:

Be it known that I, GEORGE A. JOHNSON, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is to provide 15 a draft rigging of relatively low capacity on forward movement of the draw bar, and relatively high capacity in buffering movement of the draw bar.

It constitutes an improvement upon my 20 invention disclosed in my copending application, Serial No. 725,603 filed October 14, 1912.

In the drawings Figure 1 is a side elevation partly in central longitudinal section 25 on line 1—1 of Fig. 2 of a draft rigging embodying my invention. Fig. 2 is a plan view partly in horizontal section on line 2—2 of Fig. 1. Fig. 3 is a side elevation partly in central longitudinal section showing the 30 position of the parts of the draft rigging on full forward movement of the draw bar. Fig. 4 is an elevation partly in central longitudinal section showing the parts of the draft rigging under full compression in buff. 35 Fig. 5 is a perspective view of the follower, and Fig. 6 is a perspective view of the clip.

Referring to the drawings 5, 5 represent center sills or parts of the car frame to which the draft rigging is attached, 6 the 40 end sill, 7 the buffer block, 8 the draw bar carry iron—all of usual construction.

9 represents a draw bar having the lateral slot 10, 11 a yoke member, 12, 12 forward stop members suitably secured to the center 45 sills, 13 the coupler key. The yoke member is forwardly provided with a hollow head 14 to receive the draw bar, said head having lateral slots 15, 15 for the passage of the coupler key 13 therethrough. The stop 50 members and center sills are provided with the slots 16, 16 suitably arranged to permit the passage of the coupler key therethrough, and longitudinally extended to permit the movement of the said key therein in buff and 55 pulling movement of the draft rigging.

Mounted between the center sills is the compression resisting member 17. The said compression resisting member 17 comprises a shell 18, and spring elements 19, and friction elements 20 within the shell. The shell 60 consists of a spring cage 21, and a friction case 22. The spring cage 21 is preferably rectangular in shape, and having a hollow interior 23, and closed at its forward end by the preferably integral plate 24, which 65 serves as a front follower, and in normal position or forward movement of the gear engages the front stop members 12, 12.

The friction case 22 is at the rear end of the shell, and is preferably integral therewith. In preferable construction it is cylindrical in shape, having the internal friction face 25, and is open at its rear end 26. Within the friction case are the friction elements 20, which consist of a wedge 27 and 70 annularly arranged segmental friction shoes 28, preferably three in number, the said shoes each having a friction face 29 for engagement with the internal friction face 25 of the friction shell, and each being provided on the inner surface with a wedging face 30 between which and the wedging face 31 of the wedge is interposed the anti-friction roller 32.

The wedge 27 is provided at its rear end 85 with a recess 33 to receive the nut 34 of the short connecting rod 35, which passes through said wedge and through the clip 36, the head of said rod being disposed within the recess 37 in the forward face of the 90 clip 36. The clip 36 serves with the connecting rod to hold the friction members in assembled position.

Within the spring cage and between the spring elements therein and the friction elements within the friction case is disposed the follower 38 comprising a transverse plate 39 and a boss 40 extended rearwardly therefrom. The boss 40 is of suitable size and shape to engage the forward ends 41 of the 100 friction shoes on buffering movement of the draft rigging, and in preferable construction is of a general cylindrical shape. It is provided with a vertical slot 42 to receive the preferably flat vertical key 43, which 105 passes through the slots 44, 44 provided in the upper and lower portions of the spring cage, and also passes through the slots 45, 45 provided in the upper and lower limbs 46 and 47 respectively of the yoke 11. The 110

lower limb 47 of the yoke rests upon the bottom tie plate 48, and thus supports the gear between the draft sills. The upper tie plate 49 is suitably secured between the draft sills to clear the upper limb 46 of the yoke.

The spring elements 19 in preferable construction comprise a pair of outer springs 50, 50 in twin arrangement, each with an inner spring 51 nested within. The spring elements are seated at their forward ends against the plate 24 of the spring cage, and at their rear ends against the follower 38. The slots 44, 44 in the spring cage are suitably longitudinally extended to permit the forward movement of the key 43 therein to compress the spring elements on forward movement of the yoke.

It will be apparent that on forward movement of the draw bar 9, the shell 18 being held against forward movement by the forward stop members 12, 12, the yoke 11 through the connecting key 43 draws the follower 38 forward against the compression resisting spring elements 19, and without bringing into action the friction elements 20.

The slots 15, 15 in the yoke head are sufficiently extended rearwardly to permit the rearward movement of the coupler key 13 therein on buffing movement of the draw bar. On such buffing movement the draw bar engages the shell 18, and forces it rearwardly. The wedge 27 is in engagement with the rear stop member 52, which in preferable construction is a block secured between the center sills, and the friction case 22 is moved rearwardly in the inclosed friction elements, the follower 38 through its boss 40 engages the friction shoes, and the spring elements are thus brought into action with the friction elements.

I claim:

1. In a draft rigging for railway cars, draft members, stop members, a draw bar, and a yoke in combination with a shell, friction elements and spring elements within the shell, a follower between said elements, and connected to the draw bar, and adapted to compress the spring elements against the shell on forward movement of the draw bar, and to operatively connect the spring and friction elements on rearward movement of the draw bar.

2. In a draft rigging for railway cars, draft members, stop members, a draw bar, and a yoke member in combination with a compression resisting member comprising a shell, friction elements and spring elements within the shell, a follower between said elements, a key connecting said follower to the yoke member, the spring elements being seated between said follower and the forward end of the shell, and the follower being adapted to compress the spring elements on forward movement of the draw

bar, and to engage both friction and spring elements in rearward movement of the draw bar.

3. In a draft rigging for railway cars, draft members, stop members, a draw bar, and a yoke member in combination with a compression resisting member comprising a spring cage adapted to engage the forward stop members, and spring elements within said cage, and a friction case connected to the spring cage, friction shoes and a wedge within said case, said wedge being adapted to engage the rear stop member, a follower between the friction shoes and the spring elements, and connected to the yoke, the said follower being adapted to compress the spring elements on forward movement of the draw bar, and to engage the friction shoes in rearward movement of the draw bar.

4. In a draft rigging for railway cars, draft members, stop members, a yoke member and a draw bar, in combination with a shell, springs and friction elements within the shell, a follower disposed between the friction elements and the springs, said follower being connected to the yoke member and adapted to compress the springs against the shell on forward movement of the draw bar, and to engage the springs and friction elements in their compression resisting action on rearward movement of the draw bar.

5. In a draft rigging for railway cars, draft members, stop members, a yoke member and a draw bar, in combination with a shell, springs and friction elements within the shell, a follower disposed between the friction elements and the springs, said follower being connected to the yoke member and adapted to compress the springs against the shell on forward movement of the draw bar, and to engage the springs and friction elements in their compression resisting action on rearward movement of the draw bar, said follower comprising a plate having a rearwardly extending boss adapted to engage the friction elements.

6. In a draft rigging for railway cars, draft members, stop members, a yoke member and a draw bar, in combination with a shell, springs and friction elements within the shell, a follower disposed between the friction elements and the springs, said follower being connected to the yoke member and adapted to compress the springs against the shell on forward movement of the draw bar, and to engage the springs and friction elements in their compression resisting action on rearward movement of the draw bar, said follower having through said yoke a sliding connection with the draw bar.

7. In a railway draft rigging, a draw bar, stop members, draft members and a yoke, in combination with a shell having at its forward end a spring cage, and at its rear end

- a friction case, springs within the spring cage, and friction elements in the friction case, a follower between the springs and friction elements, the said follower being connected to the draft yoke, and adapted to compress the springs on forward movement of the draw bar without bringing the friction elements into action.
8. In a railway draft rigging, a draw bar, stop members, draft members and a yoke, in combination with a shell having at its forward end a spring cage, and at its rear end a friction case, springs within the spring cage, and friction elements in the friction case, a follower between the springs and friction elements, the said follower being connected to the draft yoke, and adapted to compress the springs on forward movement of the draw bar, and to engage the springs and friction elements on rearward movement of the draw bar.
9. In a railway draft rigging, draft members, front and rear stop members, a draw
- bar, and a compression resisting member comprising a longitudinally movable shell, spring elements, friction shoes and a wedge within the shell, the wedge being stationary and engaging the rear stop member.
10. In a railway draft rigging, a draw bar, front and rear stop members, a yoke, and a longitudinally movable shell, a follower, springs, friction shoes and a wedge within the shell, the said follower being connected to the yoke, and adapted to compress the springs against the forward end of the shell on forward movement of the draw bar without bringing the friction shoes into action, the wedge being stationary, and the shell moving rearwardly, and bringing the friction shoes and springs into action on rearward movement of the draw bar.

GEORGE A. JOHNSON.
